UNITED STATES PATENT OFFICE.

FREDERICK GOLDENBOGEN, OF CHICAGO, ILLINOIS, ASSIGNOR TO THE
BRUNSWICK-BALKE-COLLENDER COMPANY, OF SAME PLACE.

COLUMN FOR INTERIOR CABINET-WORK.

SPECIFICATION forming part of Letters Patent No. 681,417, dated August 27, 1901.

Application filed February 13, 1901. Serial No. 47,113. (No model.)

To all whom it may concern:

Be it known that I, FREDERICK GOLDENBOGEN, of Chicago, Cook county, State of Illinois, have invented a new and useful Improvement 5 in Columns of Interior Cabinet-Work; and I do hereby declare that the following is a full, clear, and exact description of the same, reference being had to the accompanying drawings, forming part of this specification.

My invention relates to the art of interior cabinet-work or to such decorative woodwork as is usually done in fitting up bar-rooms, offices, &c., and more especially to such portions of such work as comprise the architectural elements of columns.

Previous to my invention in the doing or manufacture of interior cabinet-work those parts of the woodwork comprising columns or column-like elements have been made either solid of some comparatively cheap (and soft) wood and then veneered to get beauty of appearance or they have been composed of a form made of pieces of thick common wood glued together and then veneered on the exterior surface. In many kinds of work the making thus of these parts of the whole design either solid or sometimes of centrally-hollow heavy forms of common wood, with the exterior veneered, these elements are not only costly of manufacture or production, but, furthermore, they are heavy, rendering the handling and transportation of the cabinet-work laborious and costly, and the veneered surface affected partially by the shrinkage and warpage of the soft-wood cores or forms is very liable to soon crack or check, spoiling the appearance of the cabinet-work, which may have been perfected with a high state of superficial finish.

My invention has for its object to produce the column-like members (or rather the body portions thereof) of all such artistic wood-work or cabinet-work in the forms of mere shells of wood formed of several thicknesses of veneers glued together in such manner that the completed members will not only be much lighter than those heretofore made, but will, while being equally as strong, have no liability to warp or shrink out of form nor to crack or check superficially; and to these

main ends and objects my invention may be said to consist in making such columns or column-like members of several veneers or several thin layers of wood glued together in 55 the proper shape with a diametrical stay-board, all as will be hereinafter more fully described and as will be found most particularly pointed out in the claim of this specification. 60

To enable those skilled in the art to which my invention relates to understand and practice the same, I will now proceed to more fully explain it, referring by letters to the accompanying drawings, which form part of 65 this specification and in which I have shown my said invention carried into effect precisely as I have so far extensively and successfully practiced it.

In practicing my invention so far I have 70 applied it mainly in the manufacture or construction of bar-room or café cabinet-work—such as bars, back-bars, buffets, &c.—and in the drawings the elements or cabinet-work members which I have shown are such as I 75 have used in this special line of interior wood-work, though of course the novel features I have shown may under an infinite variety in the shapes and proportions of these parts be utilized in other branches of interior cabinet 80 or artistic woodwork.

In the drawings, Figure 1 shows in elevation a cylindrically-shaped hollow column provided with a base and a capital and made according to my invention. Fig. 2 is an end 85 view of the body or main tubular part of the column, showing its diametrically-arranged interior stay-board and illustrating the use of this device in the course of finishing up the column. Fig. 3 is a cross-section at the 90 dotted line x x of Fig. 1. Fig. 4 is a partial horizontal section at the line x x of Fig. 1, but drawn on an enlarged scale (about full size) to better show the several thin thicknesses of wood or the series of veneers of 95 which the body portion of the column is composed. Fig. 5 is a partial vertical section at the line 5 5 of Fig. 1 to illustrate how the upper and lower ends of the body portion of the column are fitted within grooves made, 100 respectively, in the top and bottom blocks of the column.

In the several figures the same part will be found always designated by the same character of reference.

A is the body portion, b the base-molding, 5 and C the cap or neck molding, of the column member of some artistic design of back bar piece of cabinet-work. The part or member A, instead of being composed, as usual prior to my invention, of a solid piece of common 10 wood having its exposed surface simply veneered with some expensive wood of beautiful appearance when finished up, is composed of several thin layers of wood or of several veneers—in the case shown (see Fig. 15) five in number—which are glued together in the formation of the shell or hollow body portion shown, the set forming the shell having their abutting edges forming a joint at the line c. (See Fig. 3). All the layers except 20 the outer one may be composed of comparatively cheap, but sufficiently strong and durable, wood or woods, while only the outer layer or veneer 5 (see Fig. 4) need be composed of some more expensive and beautiful 25 wood, destined to give the finished column device the desired appearance or esthetical effect.

In making the portion A of the column the following *modus operandi* has so far been 30 practiced with perfect success: Having had made a wooden former or core of the proposed size and shape of the column to be produced, (except that it must have a diameter equal to that of the proposed column-body 35 minus twice the thickness of the set or series of veneers to be used,) I first take the outer fine-wood veneer, (see 5, Fig. 4,) which, like the other four, has been cut to measure in one direction equal to the height of the said 40 column-body and in the other direction a little more than the circumference thereof, and apply to what is to be its inner surface a coating of glue. I then apply glue to both surfaces of the veneer 4 and place it in contact with 45 No. 5, and so on. I coat with glue and put together the five veneers (see Fig. 4) in their normal or flat condition, except that no glue is applied to the exposed surface of veneer 1, the veneers being cut and put together so 50 that while the grain of the wood of No. 5 runs in the direction of the length of the column-body A that of No. 4 runs transversely, that of No. 3 vertically, that of No. 2 transversely, and that of No. 1 vertically, in order 55 that the grains of the several layers of wood will cross each other, whereby the united series forms a wooden mass which will not be liable to warp, split, or check, which is a matter of great importance. Preferably 60 while this operation of putting together the glue-coated veneers is being performed the wooden core or former is heated in a steam-heating box supplied with inclosed pipes in such a manner as to effectuate a thorough 65 heating of said core to a pretty-high temperature necessary to produce good results, and at the same time, and preferably in the same

heater, a sheet-metal caul is thoroughly warmed up to a pretty good temperature, for a purpose to be presently explained. It is 7c necessary to thoroughly grease the exterior peripheral surface of the wooden core and also the inner surface of the sheet-metal caul or binder to prevent the adherence to them, respectively, of the inner and outer surfaces of 75 the set of veneers, (1 to 5, inclusive,) and after the removal of the core and caul from the heater and while both are hot the workman or operative, with the assistance of a helper, properly bends and places around 80 about the hot former the mass of united layers of wood, at the same time wrapping around the mass of veneers the sheet-metal heated caul or binder until its meeting edges, which, as usual, are provided with edge strips adapted to be clamped together, nearly contact, when they are fastened together with hand-screw clamping devices. The aggregated plies of veneering, as before remarked, having been cut big enough to slightly more than 85 equal the circumference of the core, their meeting edges do not form the butt-joint, (seen at c, Fig. 3,) but come together, and being sharply bent outwardly project in a radial direction slightly beyond the periphery 90 of the core. Great care must be exercised in placing the mass of veneers around and clamping them, with the hot caul, onto the hot core to avoid any twisting or misplacement of the layers, which will spoil the job, and at the 95 same time care must be taken to get the aggregated layers of wood arranged to perfectly and tightly envelop the core. The core thus embraced by the securely-clamped-on set of veneers is then put one side over night for 100 the glue joints to harden. The glue joints or the unions between the several veneers will not, it is found, completely harden in this time; but being sufficiently set for the purpose the operation of making the butt-joint at c is thus proceeded with, and the body portion A of the column is perfected or 105 finished, as follows: The nearly-contacting bent-out meeting edges of the veneers are carefully cut or trimmed down and bent into 110 position until they will just meet around the core to form a perfect butt-joint. Then the stay-board or diametric brace E is placed within the hollow mass (after the removal of 115 the core) and the meeting ends or edges of the 120 mass of veneers all securely glued thereto. In effectuating this union of the meeting edges of the veneers, however, with the diametric stay-board E one edge of the veneers is first glued to the adjacent edge of said 125 board, and the united parts being clamped together with hand-screw clamps the joint is allowed to thoroughly harden. Then the other edge is glued to the said stay-board 130 edge, and the united parts are this time securely clamped together by encircling bands, arranged at suitable distances apart, that are tightened up around about the hollow column-body and its internal stay E, so as to in-

sure the completion of a perfect butt-joint, as seen at *c* in the drawings. The stay-board *E*, it must be understood, is gotten out to exactly correspond in width to the internal diameter of the hollow column-body *A* and with its longer opposite edges turned off in a lathe to match to the curvature in cross-section of the bore of the part *A*, as shown. After the work shall have progressed, as just above explained, and when all the glued unions shall have perfectly hardened the column may be put into a lathe on the center-points *e*, (see Fig. 2,) on which the stay-board *E* was centered when its edges were turned off and its ends trued up or turned off to exactly the desired ultimate length of the body *A*, the exterior surface of *A* sandpapered or otherwise finished up as may be desired, and each end of the diametrically-arranged stay-board turned off at the localities *i* (see Fig. 2) to make said board shorter than the tubular veneer part *A* for a purpose to be presently explained. After this the middle end portions of said board (used for centering the work in the lathe) may be cut down or off to permit the uniting of the column-body *A* with the base and neck moldings *b* and *C* in the following manner: In the under side or lower surface of the molding or cap *C* and in the top surface of the base-molding *b* are turned circular grooves *m* (see Fig. 5) of exactly the right size to receive or accommodate within them the ends of the tubular veneer-formed body *A* and of sufficient depth to take in the ends of said tubular part *A* to an extent sufficient for the purpose of effectuating a secure glued union of the parts. Of course any desired sort or pattern of fancy capital and base are designed to be applied, respectively, over the part *C* and beneath the part *b* in the usual manner.

I have shown and described only so much of a given pattern of woodwork as appears to be necessary for the purpose of illustrating my invention. Of course the *modus operandi* I have specified may be varied and the work done somewhat differently without departing from my invention, which in practice so far I have carried into effect in the manner explained.

I have found by a thorough test of my invention during a comparatively long period of time that not only are the column-bodies *A* and the whole cabinet structure of which they form part stronger, while at the same

time much lighter than any heretofore devised cabinet-work known to me, but, furthermore, which is of greater moment, my improved hollow column-body portions of the work will not warp, crack, or check, as do columns otherwise made. Thus made the shell *A* will be vastly more enduring in its original perfect condition than it is possible to have a column made of either a solid or of a hollow but very thick body of common (soft) wood simply veneered to get the requisite superficial beauty of appearance.

As before remarked, all the layers or veneers except the exterior one 5 (see Fig. 7) may be made of comparatively cheap wood or woods of suitable quality, while the outer layer 5 is a veneer of such finer wood as will match or harmonize with the other wooden surfaces of the finished structure and lend to the latter the desired esthetical effect.

If found expedient, the series of veneers may be combined successively so that their several meeting edges will break joints—that is, so that the several layers will meet at various points or lines in the circumference of the shell instead of all meeting at the line *e*, as shown. Of course under circumstances rendering it desirable or expedient either a less or a greater number of veneers than I have shown may be used to produce the body portion *A* of a given size, and in the judgment of the skilled workman the thickness of the veneer-pieces may be varied or the inner four thicknesses (of "culls") may each be thicker than the outer veneer 5 of fine wood.

Having now so fully explained my invention that those skilled in the art of cabinet-work can practice the same either in part or in whole and either under the precise methods of doing the work I have described or under some other practical mode of procedure,

What I claim as new, and desire to secure by Letters Patent, is—

As an improved product, a hollow column for cabinet-work, composed of a series of united veneers comprising the body portion; and a diametrically, interiorly, arranged stay-board; these parts being united and combined substantially as hereinbefore set forth.

In witness whereof I have hereunto set my hand this 9th day of February, 1901.

FREDRICK GOLDENBOGEN.

In presence of—

FRED. J. LOUVE,

W.M. GJERDE.
